(57) CLAIM

I claim the ornamental design for a baby teether, as shown and described.

DESCRIPTION

FIG. 1 is a front perspective view of a baby teether. FIG. 2 is a back perspective view of a baby teether. FIG. 3 is a front elevation view of the baby teether; and, FIG. 4 is a back elevation view of the baby teether. Features shown in dotted lines are for illustration purposes only and form no part of the claimed design.
